UNITED STATES PATENT OFFICE.

EDWIN W. JONES, OF IPSWICH, ENGLAND.

APPARATUS FOR COMPRESSING AIR AND OTHER ELASTIC FLUIDS.

1,107,957.

Specification of Letters Patent. Patented Aug. 18, 1914.

Application filed February 3, 1913. Serial No. 745,978.

To all whom it may concern:

Be it known that I, EDWIN WALTER JONES, engineer, a British subject, residing at Ipswich, Suffolk, England, have invented 5 certain new and useful Improvements in Apparatus for Compressing Air and other Elastic Fluids, of which the following is a specification.

This invention relates to apparatus for 10 compressing air or other elastic fluids, and its object is to increase the efficiency of such apparatus.

In multistage air compressors the cylinders of consecutive stages of compression 15 are usually made of consecutively decreasing volumes and communicate with each other through intercoolers, each cylinder being provided with an inlet and an outlet valve. The second or other intermediate cylinder 20 works as follows:—At the beginning of the suction stroke of the piston the inlet valve opens and air from the intercooler on the admission side enters the cylinder, while the outlet valve remains closed. At the beginning 25 of the compression stroke the inlet valve closes, the air in the cylinder is compressed during the compression stroke, until the pressure is sufficient to open the discharge valve against the pressure existing 30 in the succeeding intercooler, when the delivery valve on the cylinder opens and the air enters the intercooler. Cooling therefore takes place before and after compression, but only to a slight extent during compression, for although in some cases the 35 walls of the cylinder are to a certain extent cooled, such cooling is necessarily much slower than the cooling in pipes which have thin walls and a comparatively large cooling surface. The efficiency of multistage 40 compressors and the speed at which they can be run depends largely on the rapidity and completeness of cooling.

According to this invention the second or 45 other cylinder of even number in the series is constructed without the usual inlet or outlet valves, the supply- and delivery-pipes communicating freely with the interior of the cylinder, so that the cylinder is always 50 in free communication with the intercooler. Consequently during the compression stroke of the piston the said intercooler forms part 55 of the compression space, the air is compressed therein, and consequently effective cooling takes place during compression, since the intercooler consists of thin walled

pipes surrounded by water (though they might be air cooled). It will be understood, that at the end of the compression stroke a portion of the air compressed and cooled in 60 the intercooler enters the next cylinder in the series. During the subsequent return or suction stroke of the piston the air remaining in the intercooler expands against the piston, thereby returning to it a portion of 65 the work done during the compression stroke. By these means more rapid and effective cooling takes place.

The intermediate cylinder of a three-stage compressor may be closed at both ends, one 70 end (the valveless end) being connected through the intercooler with the low-pressure cylinder and also with the high-pressure cylinder, in the manner described above, while the other end is connected through a 75 suction valve with the atmosphere and through a discharge valve with the pipe leading from the intercooler to the valveless end of the intermediate cylinder, the latter in addition to performing the ordinary function of a second stage compressor, acting 80 also as an auxiliary low pressure cylinder, whose output is added to the volume of air compressed in the first or low-pressure cylinder. This auxiliary low-pressure effect 85 of the intermediate cylinder may be set in action, when required, according to the pressure of air in the receiver, by means of a device adapted to control the position of a valve, preferably the suction valve, of the 90 cylinder.

The motion of the pistons may be produced by a piston rod connecting the low-pressure with the intermediate piston and a lever and link mechanism acting on the said piston 95 rod, or it may be derived from a crank shaft and a pair of connecting rods acting on the low-pressure and the intermediate piston, in which case the said pistons are constructed as trunk pistons and the intermediate cylinder 100 is open at one end, or alternatively a guide may be provided for one or each of these cylinders, for example the low-pressure cylinder may have a trunk piston and connecting rod and the intermediate piston 105 a connecting rod guide, so as to utilize both ends of the intermediate piston in the manner described above.

In the accompanying drawings Figure 1 is a vertical section of a vertical three-stage 110 compressor embodying my invention, Fig. 2 is a side view of the driving mechanism at

right angles to Fig. 1, Fig. 3 is a vertical section on a larger scale of a pair of valves of a double-acting intermediate cylinder provided with automatic regulation for the low pressure side.

In these drawings *a* is the low-pressure cylinder and *c* the high pressure cylinder placed axially above the low-pressure cylinder. Their pistons *d* and *f* are rigidly connected and single-acting. The intermediate cylinder *b* is mounted on the opposite side of the driving mechanism and coaxial with the other cylinders. As shown by the drawing, the sectional area of the cylinder *b* is substantially less than that of cylinder *a*, account being taken of the sectional areas of the piston rods. This is essential for the desired effect of my invention, and in practice the volume of the low pressure cylinder *b* is preferably larger than that of the compression space comprising the intermediate cylinder and the intercooler.

The low pressure piston *d* is connected with the intermediate piston *e* by a piston rod *g*, on which is mounted a cross head *h* set in motion by a pair of oscillating levers *i* through the intermediary of links.

The air, which has been compressed in the cylinder *a* provided with an ordinary inlet valve *a*¹ and outlet valve *a*² passes through the outlet *l* into the pipes *m* of an intercooler and then through the admission port *n* directly into the lower end of cylinder *b* without the intervention of a valve. The upper end of the intercooler communicates with the pipe *p* leading to the inlet valve *q* of the high-pressure cylinder *c*, and the air which has been compressed in the latter escapes through an outlet controlled by a valve *r* into the discharge pipe *s* leading to a receiver *t*. The low-pressure cylinder *a* has a suction valve *a*¹ and a delivery valve *a*², as mentioned above.

The compression cylinders are secured to the side of a main frame or casting *u*.

It will be understood, that at the end of the downward stroke of the intermediate piston *e* a portion of the air compressed in the lower part of cylinder *b* and then cooled in the intercooler enters the cylinder *c*. During the subsequent return or upward stroke of the piston *e* the air remaining in the intercooler expands against the piston, thereby returning to it a portion of the work done during the down stroke.

It will be noticed that the same system of cooling pipes serves alternately for conducting compressed air from the low-pressure cylinder *a* to the intermediate cylinder *b* and for conducting the air compressed in the latter to the high-pressure cylinder *c*, the intercooler forming part of the compression space.

The upper end of the intermediate cylinder *b* is closed by a cover provided with a

suction valve box *b*¹ and a discharge valve box *b*², from which a branch *b*³ leads to the air conduit extending from the pipe *l*, through the intercooler to the port *n*. The upper side of the piston *e* and cylinder *b* may be rendered ineffective, that is to say, the cylinder may be rendered single acting, preferably by keeping the suction valve *b*¹ open during the forward and backward stroke of the piston *e*, so that the pressure above the piston cannot become substantially higher, than that of the atmosphere, and the discharge valve *b*² will remain closed, or the suction valve may be held closed, thus allowing the air above the piston, which is not delivered through delivery valves to be alternately expanded and compressed. The suction pipe *v* leading to the suction valve of the auxiliary cylinder may be provided with an ordinary valve *v*¹ which can be operated by hand, if it is desired to adjust the volume of auxiliary air admitted independently of the receiver pressure.

If the valves of the upper end of the cylinder *b* act in the usual manner of pump valves, the down-stroke of the piston *e* draws air into the cylinder through the suction valve *b*¹, and the subsequent up-stroke compresses the air which then escapes through the discharge valve *b*² and branch pipe *b*³ into the line of pipes connecting the cylinders *a* and *b*. The compressed air discharged from the upper end of the cylinder *b* is therefore added to that which flows from the cylinder *a* to the cylinder *b*, and the upper part of cylinder *b* may thus be made to act as an additional low-pressure cylinder. This auxiliary action of the cylinder *b* may be made dependent on the pressure of the air in the receiver *t* fed by the discharge pipe *s* of the high pressure cylinder *c*. The pressure in the receiver will vary according to the volume of air abstracted from the same for various purposes. If the volume is greater than that supplied during the same time by the pipe *s*, the pressure will fall, in which case it is desirable, to increase the supply of air by increasing the output of the low-pressure stage of the compressor. This may be done automatically by a device adapted to release the suction valve *b*¹ of the cylinder *b*, when the pressure in the receiver falls below a given minimum and which retains the valve *b*¹ in the open position, when the pressure in the receiver has risen to a given maximum. Any known device suitable for this purpose may be employed, and I make no claim to any special construction, but may adopt, for instance, that shown by Fig. 3. In this figure, *b*¹ indicates the suction valve, whose spindle is provided at the top with a collar *b*⁴ resting on a spring *b*⁵ adapted to hold the valve in its closing position. Into the valve box is screwed a casing *b*⁶, which contains at the

110
115
120
125

top a vertically movable box b^7 supported by a spring b^8 and containing a spindle b^9 which terminates a short distance above the spindle of the valve b^1 . The upper part of the casing b^6 extends into a cap b^{10} , provided at the top with a socket b^{11} for a pipe (not shown) communicating with the receiver. A duct b^{12} leads from the said socket to the interior of the cap b^{10} . The casing b^6 has 10 lateral openings communicating with the port b^{13} open to the atmosphere, while the port b^{14} communicates with the upper end of the cylinder b . In the position shown by the drawing the valve b^1 is free to open and close. If the pressure in the receiver exceeds the desired maximum, the spring box b^7 is forced down, and its spindle b^9 forces down the valve b^1 , so as to keep it open until the pressure in the receiver has dropped sufficiently for allowing the valve to close and act in the normal manner; b^2 is the delivery valve communicating with the interior of the cylinder b through the port b^{14} and with the pipe b^3 through the port b^{15} .

26. What I claim is:—

1. In an apparatus of the class described, the combination of a single-acting low-pressure cylinder and a single-acting high-pressure cylinder with an intermediate compression cylinder closed at both ends, one end being in constant communication with the outlet valve of the low pressure cylinder and with the inlet valve of the high pressure cylinder through an intercooler so that the intercooler forms part of the compression space at the intermediate compression stage, the end of the intermediate cylinder opposite to the constantly open end of the same having an inlet controlled by a suction valve and an outlet controlled by a discharge valve toward the conduit connecting the constantly open end of the intermediate cylinder with the low pressure cylinder, so that while one end of the intermediate cylinder receives air from the low-pressure cylinder, the opposite end may act as an auxiliary low-pressure cylinder, substantially as described.

2. In an apparatus of the class described, an intermediate compression cylinder closed at both ends, one end being in constant communication with the outlet valve of the low pressure cylinder and with the inlet valve of the high pressure cylinder through an intercooler so that the intercooler forms part of the compression space at the intermediate compression stage, the end of the intermediate cylinder opposite to the constantly open end of the same having an inlet controlled by a suction valve and an outlet controlled by a discharge valve toward the conduit connecting the constantly open end of the intermediate cylinder with the low pressure cylinder, so that while one end of the intermediate cylinder receives air from the low-pressure cylinder, the opposite end may act as an auxiliary low-pressure cylinder, substantially as described.

low-pressure cylinder the opposite end may act as an auxiliary low-pressure cylinder, and a device for temporarily rendering the auxiliary low-pressure cylinder ineffective, substantially as described. 70

3. In an apparatus of the class described, the combination of a single-acting low-pressure cylinder and a single-acting high-pressure cylinder with an intermediate compression cylinder closed at both ends, one end being in constant communication with the outlet valve of the low pressure cylinder and with the inlet valve of the high pressure cylinder through an intercooler so that the intercooler forms part of the compression space at the intermediate compression stage, the end of the intermediate cylinder opposite to the constantly open end of the same having a suction valve and a discharge valve communicating with the conduit connecting the constantly open end of the intermediate cylinder with the low pressure cylinder, so that while one end of the intermediate cylinder receives air from the low pressure cylinder the opposite end may act as an auxiliary low pressure cylinder, a receiver for the air discharged from the high pressure cylinder, and a device adapted to control the position of one of the valves of the intermediate cylinder according to the pressure in the said receiver substantially as described. 90

4. In an apparatus of the class described, the combination of a single-acting low-pressure cylinder and a single-acting high-pressure cylinder with a compression cylinder closed at both ends, one end being in constant communication at one end through an intercooler with the outlet valve of the immediately preceding compression cylinder and with the inlet valve of the immediately succeeding compression cylinder, so that the said intercooler forms part of the compression space whose volume, including that of the said intercooler, is less than that of the immediately preceding compression cylinder, substantially as described. 100 105

5. In an apparatus of the class described, an intermediate compression cylinder in constant communication with the outlet valve of the low-pressure cylinder and with the inlet valve of the high pressure cylinder through an intercooler, so that the intercooler alternately serves to conduct air from the low-pressure to the intermediate cylinder, and from the intermediate cylinder to the high-pressure cylinder, this intercooler forming part of the compression space of the intermediate compression stage, substantially as described. 110 115 120

6. In a vertical compressor having an intermediate cylinder in constant communication at one end with the outlet valve of the low-pressure cylinder and with the inlet valve of the high pressure cylinder through an intercooler, the combination of a driving mechanism for the pistons, with a low-pres- 125 130

sure cylinder and a piston and a high pressure cylinder and piston arranged axially behind each other on one side of the driving mechanism, an intermediate compression cylinder and piston situated on the opposite side of the driving mechanism in line with the other cylinders, an intercooler, and pipe connecting the intermediate cylinder with the low and the high-pressure cylinders

through the intercooler, substantially as described.

In testimony whereof I have hereunto set my hand in presence of two subscribing witnesses.

EDWIN W. JONES.
